ARC LAMP

Harold R. Benson, Maywood, Ill., assignor to
 NuArc Company, Chicago, Ill., a corporation of
 Illinois

Application March 3, 1950, Serial No. 147,560

17 Claims. (Cl. 314—51)

1

The present invention relates generally to arc lamps and more particularly to an arc lamp especially adapted for use in the graphic arts industry where an accurately controlled light source of a constant predetermined intensity is desired, as in photographic departments and the like.

Arc lamps have heretofore been extensively employed in the graphic arts industry since they provide a means for producing in an efficient manner a very intense source of illumination. Conventionally such lamps comprise carbon electrodes associated with a suitable reflector with means for controlling the feed of the carbon electrodes. It is desirable that such arc lamps produce a definitely controlled light which is exactly the same each time it is used as far as the intensity and Kelvin temperature is concerned, so that definite standards for exposures in the graphic arts industry may be maintained. Heretofore such arc lamps have been unsatisfactory in that the light produced is not steady, and if with such prior lamps a plot of foot candles or Kelvin temperature versus time were made, a curve having considerable variation would be obtained. This is due to numerous factors. For example, it is well known that substantial variations in the voltage of the source supplying the electrical energy for the arc lamp constantly occur. Also, the carbons employed are not absolutely uniform in that they have hard and soft spots which burn at different rates of speed. It would be desirable to provide an arc lamp with improved control means whereby the Kelvin temperature and foot candles output would remain substantially constant over long periods of time, thereby eliminating guess work with respect to exposure time in the graphic arts industry with the resultant extensive reshooting heretofore necessary. It is furthermore desirable to provide a single source light for the graphic arts industry which assures clear and sharp line definition in connection with photographic work with improved automatic means for maintaining a constant light intensity regardless of the impurity of the carbon electrodes or the variations in line voltage. With such an arrangement long exposures resulting in "fuzzy" line definition will become a thing of the past and sharp, perfect exposures producing clear, sharp line definition are the usual result. Obviously, any reduction in exposure time saves money since it cuts down the power consumption of the arc lamp and reduces the time which the operator must spend in waiting for exposures, to say nothing of retakes or reshooting which is so commonly the case with prior art arrangements.

It is an object of the present invention to provide a new and improved arc lamp particularly well adapted for use in the graphic arts industry.

It is another object of the present invention

5 to provide an arc lamp with means for definitely and accurately controlling the light so that it has the same intensity at all times, independently of voltage variations or the like, thereby enabling definite standards of exposure to be established.

10 It is another object of the present invention to provide an arc lamp which is more economical, more efficient and produces more satisfactory light than prior art arrangements and which furthermore will give many years of foolproof service.

15 Still another object of the present invention resides in the provision of an improved arc lamp which requires but a fraction of the power employed in prior art devices, which enables the exposure time in the graphic arts industry to be greatly reduced and at the same time permits a remarkable step up in production.

20 It is a further object of the present invention to provide an improved arc lamp which is effective at the flip of a switch to produce a high intensity light without flicker and without substantially any variation in intensity or color.

25 Still a further object of the present invention resides in the provision of an improved arc lamp with automatic control means for maintaining the arc at a constant length regardless of the impurities in the carbon electrodes, and regardless of line voltage variations.

30 Further objects and advantages of the present invention will become apparent as the following description proceeds and the features of novelty which characterize the invention will be pointed out with particularity in the claims annexed to and forming a part of this specification.

35 For a better understanding of the present invention, reference may be had to the accompanying drawings in which:

Fig. 1 is a perspective view of an arc lamp 40 embodying the present invention;

Fig. 2 is a schematic circuit diagram illustrating the electrical control and power circuits associated with the arc lamp of Fig. 1;

Fig. 3 is a vertical sectional view taken along 45 line 3—3 of Fig. 1 with certain cover or housing portions removed;

Fig. 4 is a rear view looking in the direction of the arrows 4—4 of Fig. 1 with the mechanism cover removed, more clearly to illustrate certain 50 details of the present invention;

Fig. 5 is an enlarged detailed view, partly in section, of portions of the apparatus viewed from the same direction as in Fig. 4;

Fig. 6 is a sectional view taken on line 6—6 55 of Fig. 5;

Fig. 7 is a sectional view taken on line 7—7 of Fig. 5 with certain parts of the apparatus shown in phantom;

Fig. 8 is an enlarged sectional view of only a

2

portion of the apparatus taken along line 8—8 of Fig. 4;

Fig. 9 is an enlarged view of a portion of the apparatus shown in Fig. 3;

Fig. 10 is a side elevational view illustrating a modification of the present invention with respect to the carbon electrode supporting means; and

Fig. 11 is a sectional view taken on line 11—11 of Fig. 10.

In accordance with the present invention, there is disclosed an arc lamp which provides constant illumination under all conditions by maintaining a constant current flow through the arc whether the voltage is high or low, and regardless of the impurities in the carbons forming the electrodes of the arc lamp. There is provided an improved striking means for causing striking of the arc which insures straight line motion of the electrodes and an improved mechanism and control means for causing simultaneous movement of the carbons to insure an arc of the same illumination intensity at all times. Transformer means are included to provide a high arc current with power factor correction means to provide a minimum power consumption. The carbons are fed automatically to maintain a uniform gap in response to a sensitive current relay which maintains a predetermined constant current flowing through the carbon electrodes. This relay controls a motor feed for the carbons maintaining them the same distance apart regardless of the burning rate of the carbons, thereby insuring exactly the same light each time the lamp is used. With this arrangement it is immaterial whether the line voltage fluctuates, which it is wont to do.

Referring now to the drawings and particularly Fig. 1 thereof, there is illustrated the improved arc lamp 10 of the present invention which comprises a suitable reflector 11 specifically illustrated as having a rectangular cross section and being constructed in the form of a truncated pyramid. The arc lamp 10 further includes a main supporting post 12 to which the reflector 11 and associated control mechanism, disposed within a suitable housing defined by a cover member 13, is mounted as described in greater detail hereinafter. The post 12 is supported on a three armed support comprising arms 15 illustrated as disposed in a horizontal plane with the ends of the arms supported on suitable casters 17. An electrical power and control unit described in greater detail hereinafter is disposed within a suitable housing 18 supported on the arms 15, the post 12 extending up through the center of the housing 18 which latter is provided with a suitable cover 20. The housing 18 is provided with suitable louvres 21 whereby cooling air may circulate therethrough to prevent the power unit contained within the housing from reaching inordinately high temperatures. A suitable power cord 23 is connected to the means disposed within the housing 18 to supply the electrical units contained therein with electrical energy from a source not shown. Preferably the conductor 23 is adapted to be connected to an alternating current source having a potential of 220 volts, although it will be obvious from the ensuing description that the particular magnitude of voltage mentioned may vary over a wide range, and means are provided to take care of such voltage variations. A control cable 25 supplies the necessary current for the arc as well as the control current for controlling means asso-

ciated with the electrodes designated by the reference numerals 27 and 28 in the drawings.

In order to obtain an overall picture of the electrical circuit of the arc lamp of the present invention and before discussing various details thereof, reference may be had to Fig. 2 of the drawings where the electrical circuit of the arc lamp 10 is illustrated and which furthermore schematically discloses the more important elements of the device. The corresponding parts of Fig. 2 are designated by the same reference numerals as in the other figures of the drawings. As there illustrated, the power cord 23 is connected to a suitable source of electrical energy designated by the reference numeral 28. A suitable control switch 29, also shown in Fig. 1 of the drawings, controls the application of power to the power control unit disposed within the housing 18 which essentially comprises a transformer 30, control relays 31 and 32 and fine and coarse tap changing switches 33 and 34, respectively.

The transformer 30 comprises a tapped primary winding 36 and a secondary winding 37. The primary winding is provided with a plurality of taps designated by the reference numerals 38a, 38b, 38c, 38d, 38e, 38f, 38g, 38h, and 38i. The taps 38a and 38b are respectively connected to the taps 34a and 34b of the coarse adjustment tap changing switch 34, while the taps 38c, 38d, 38e, 38f, 38g and 38h are connected respectively to the taps 33c, 33d, 33e, 33f, 33g and 33h of the fine adjustment tap changing switch 33. These tap changing arrangements are provided since it is desirable for the lamp to produce a constant light intensity under any voltage conditions and it is, therefore, necessary to provide the primary transformer winding 36 with the suitable taps to accommodate the various voltages to which the unit might be connected. So that the proper settings of the tap changing switches 33 and 34 may be determined, there is provided a voltmeter 40 connected across the power source 28. The power switch 29, the tap changing switches 33 and 34 and the voltmeter 40 are suitably mounted on the cover 20 of the housing 18, as is clearly indicated in Fig. 1 of the drawings, to provide in a convenient place the control means for the arc lamp 10.

Although a particular voltage source such as 28 might nominally be termed a 220 volt source, it is well known that the voltage from such a 220 volt source might vary over a substantial range which, for example, might be the range of 200 to 252 volts. The tap 34a of the tap changing switch 34 is preferably for source voltages within the range of 200 to 225 volts so as to tend to raise the output at the secondary winding 37. The tap 34b of the tap changing switch 34 is primarily for voltages within the range of 225 to 252 volts. The tap changing switch 33 is capable of adjusting for small voltage increments within the two ranges of the tap changing switch 34 so that whether the voltage of the source 28 be close to 200, close to 252 or exactly 220 volts, there will appear across the secondary winding 37 of the transformer 30 a voltage which is always the same except for minor fluctuations of the voltage source.

The secondary winding 37 of the power transformer 30 is connected to the carbon electrodes 27 and 28 of the arc lamp 10 through power conductors 25a and 25b contained in cable 25. In this high current circuit, which for a particular embodiment constructed in accordance with the present invention had a current flow of 110

amperes, there are serially connected the windings 31' and 32' of the current relays 31 and 32, respectively. The relay 31 is a constant current control relay while the relay 32 is an arc strike relay, both described in greater detail hereinafter. The relay 31 is provided with movable contact members 31a and 31b while the relay 32 is provided with normally open contacts 32a.

For the purpose of maintaining constant the current flow through the carbon electrodes 27 and 28, which is a function of the arc gap between these electrodes, there is provided a reversible electric motor generally designated at 40 suitably connected by a driving mechanism, schematically indicated by dashed lines, with the respective electrodes 27 and 28 so that these electrodes are simultaneously moved either toward each other or away from each other, depending upon the particular direction of rotation of the motor 40. This motor 40 is illustrated as of the conventional type of motor having windings 41 and 42, respectively, sometimes referred to as a quarter phase motor. The winding 42 is adapted to be connected by the conductors 25c and 25d included in cable 25, with the taps 34a and 34b of the tap changing switch 34 which in turn are connected to the power source 23 in series with a portion of the primary winding 36 of the transformer 39 thereby to provide a control voltage of reduced potential. When the switch 29 is closed, the winding 42 is energized. However, rotation of the armature 43 of the motor 40 will not occur unless the winding 41 is also energized, and the direction of rotation will depend upon the relative polarities of the alternating potentials supplied to windings 41 and 42.

For the purpose of controlling the condition of energization of the winding 41, the current control relay 31 is provided with reversing switch contacts 31a and 31b for connecting the winding 41 to the power source with opposite connections depending upon the operating condition of the relay 31. When the winding 31' of the relay 31 is not energized, the switches 31a and 31b engage contacts 45a and 45b, respectively, so that if power is supplied to the winding 41 through the switch contacts 31a and 31b, the motor 40 will rotate in a direction to move the electrodes 27 and 28 toward each other to strike an arc therebetween. When an arc has been struck and current flows through the winding 31', the relay 31 is energized, and if the current exceeds a predetermined value the contacts 31a and 31b will engage with contacts 46a and 46b, respectively, to reverse the direction of rotation of the motor 40. The contacts 45a and 45b are connected by the conductor 25f with one terminal of the winding 41, while the other terminal is connected by the conductor 25g with the contacts 45a and 46b. If the current flow through the electrodes 27 and 28 is exactly right, the switch contacts 31a and 31b will remain in some intermediate position and the rotor 43 of the motor 40 will remain stationary. As the carbon electrodes 27 and 28 are consumed, the arc length will tend to increase, and relay 31 will maintain constant the current flowing through the electrodes by causing motor 40 to move the electrodes 27 and 28 toward each other thereby maintaining constant the intensity of the illumination produced.

The control circuit shown in Fig. 2 of the drawings includes in addition an arc strike control solenoid 50 having a movable armature 51 described in greater detail hereinafter. Specifically, the arc strike control solenoid 50 is de-

signed when energized to instantaneously separate to the desired extent the carbon electrodes 27 and 28 to draw an arc therebetween. One terminal of this solenoid 50 is connected by means of the conductor 25c to the terminal 34a and hence to one side of the alternating current source 28 through the switch 29. The other terminal of the winding of the solenoid 50 is connected by means of a conductor 25e and the contacts 32a of the strike control relay 32 to the terminal 34b and hence to the other side of the source of potential 28. When the switch 29 is closed and current flows through the carbon electrodes 27 and 28, as when these electrodes touch each other, the strike control relay 32 is energized to close its contacts 32a, with the result that the solenoid 50 is energized to move the upper carbon electrode 27 out of contacting engagement with the lower carbon electrode 28 to draw an arc therebetween.

For the purpose of supporting the reflector 11 and the carbon electrode control mechanism from the post 12 there is provided a supporting frame 54 comprising two angle members 55 and 56 held in spaced parallel relationship by cross frame members 57, 58, 59 and 60, the cross frame members being welded to the angle members 55 and 56 to provide a sort of ladder construction. The angle frame members 55 and 56 are each provided with one flange of uniform width from top to bottom while the other flanges of each angle member designated respectively as 55a and 56a have a somewhat triangular configuration with a notched central portion designated respectively as 55b and 56b to receive therein a portion of the deflector 11 as is clearly indicated in Figs. 1, 3 and 7 of the drawings. The frame 54 is supported from the post 12 on a horizontally disposed stud 60 which is threaded as indicated at 60a in Fig. 4 of the drawings into a head 61 fastened on a post 62 telescopically related with the post 12. The upper end of the post 12 is provided with a clamping means 63 best shown in Figs. 1 and 4 of the drawings, including a manually actuatable lever 65 for clampingly relating the upper post 62 and the lower post 12 in any predetermined telescopic relationship whereby the vertical position of the reflector 11 may be adjusted as desired. Preferably a suitable safety collar 67 is clamped to the upper post 62 above the clamping member 63 to limit the downward movement of the frame 54 and associated members supported thereby when it is desired to rotate the post 62 about its longitudinal axis and consequently pivot the reflector 11 about a vertical axis.

In order to permit pivoting of the frame 54 and consequently the reflector 11 about a horizontal axis in a controlled manner, there are welded to the outside faces of the angle members 55 and 56 clutch elements 70 and 71, each constructed in the form of a cone-shaped washer having an annular frictional surface. These elements are welded so as to form an integral part of the frame member 54. The supporting bolt 60 passes through suitable openings defined in the frame member 54 and the elements 70 and 71. The head 61 is also provided with a cooperating annular surface 61a, and disposed between this face 61a and the annular surface of the element 70 is a friction member 74 which may comprise a leather washer or the like. Similarly, cooperating with the annular surface of the element 71 is another annular friction member 75 which is disposed coaxially with the stud 60 and positioned between this member 75

and the element 71 is a washer 76 preferably identical with the member 14. A suitable nut 77 having a manually graspable lever portion 78 is associated with the end of the stud 60 not disposed in the head 61. It will be apparent that by means of the nut 77, a clamping force will be applied tending to press the annular surfaces of the elements or member 61, 70, 71 and 75 into intimate frictional engagement with the interposed washers 74 and 76. By loosening the nut 77, the frame 54 may be pivoted about a horizontal axis comprising the bolt or stud 60 and may be clamped in any desired angular position with reference to this horizontal axis. It should be understood that instead of smooth surfaces and frictional washers of leather or the like, that the surface 61a of the head may be provided with radial teeth or notches to engage with a corresponding surface on the element 70 to provide more positive clamping should this be desirable.

For the purpose of supporting the reflector 11 from the frame 54 there is provided a reflector support 80 in the form of a channel member of a size to be disposed between the angle members 55 and 56 in the manner best shown in Fig. 7 of the drawings. The flanges of the channel member 80 are preferably welded or otherwise secured to the flanges 55a and 56a respectively of the angle members 55 and 56. The member 80 is provided with suitable openings through the flanges thereof which are in alignment with the openings through the angle members 55 and 56 for accommodating the stud 60 defining the horizontal axis for the frame member 54. The reflector 11 is suitably bolted to the reflector support 80 by bolts 82 best shown in Fig. 3 of the drawings which bolts extend through a porcelain plate 83 closing the small end of the truncated pyramid shaped reflector. These bolts are illustrated as extending through integral flanges 11a of the reflector 11, thence through a heat insulating plate 85 and finally through the reflector support 80. The heat insulating plate 85 greatly retards the transfer of heat from the reflector 11 to the mechanism associated with the frame 54. The reflector 11 is preferably formed of metal and may have a suitable metal reflecting surface on the interior thereof. The plate 83, however, is subjected to spattering of arc particles and for this reason is preferably made of porcelain rather than metal.

The frame member 54 further includes a pair of narrow plates 86 and 88 which are arranged in spaced parallel relationship and at right angles to the cross frame members 58 and 59 as is best shown in Figs. 5 and 7 of the drawings. Preferably the plates 86 and 88 are welded to the cross frame members 58 and 59. It will be apparent that a groove extending in the direction of the frame members 55 and 56 is defined between the narrow plates 86 and 88. Disposed within this groove and extending along the frame member 54 in spaced parallel relationship are a pair of tubular members 90 and 91 each having a rectangular cross section as is clearly shown in Figs. 6 and 7 of the drawings. The central portions of the tubular members 90 and 91 are disposed within the groove defined between the members 86 and 88. The upper and lower ends of these tubular members are suitably fastened to the cross frame members 57 and 60, respectively, of the frame 54 as by fastening means 92. The adjacent faces of the tubular members 90 and 91 at the upper and lower

ends thereof are provided with elongated slots designated as 90a and 91a, respectively, at the upper ends thereof and 90b and 91b at the lower ends thereof for permitting reciprocal movement therein of an upper carbon carriage 93 and lower carbon carriage 94, respectively. The central portion of each tubular member 90 and 91 is notched in an arcuate manner as indicated at 95 for the member 91 in Fig. 5 of the drawings for a purpose which will become apparent from the following description.

In order to cause reciprocal movement of the upper carbon carriage 93 within the slots 90a and 91a of the tubular members 90 and 91, respectively, there is provided a rack 98 disposed within the tubular member 90 and having its upper end fastened as indicated at 99 to the upper carriage 93. Similarly, to support the lower carbon carriage 94 within the slots 90b and 91b of the tubular members 90 and 91, respectively, there is provided the rack 100 disposed within the tubular member 91, and having its lower end fastened as indicated at 101 to the lower carriage 94. It will be apparent that if a suitable gear member 102 centrally disposed with respect to the frame member 54 is caused to drivingly engage the racks 98 and 100, respectively, as indicated in Fig. 5 of the drawings, rotation of the gear 102 in either direction will cause simultaneous and opposite movement of the racks 98 and 100 in the direction of their longitudinal axes within the tubes 90 and 91, respectively. It will now be apparent that the arcuate notches 95 are to permit the gear 102 drivingly to engage both the racks 98 and 100. Thus, for one direction of rotation of the gear 102, the carbon carriages 93 and 94 will move toward each other and for the other direction of rotation, will move apart. When the carriages 93 and 94 are brought close together, the upper end of the rack 100 moves adjacent the carriage 93, while the lower end of the rack 98 moves adjacent to rack 94. Preferably the upper end of the rack 100 is provided with a longitudinally extending slot 100a and the lower end of the rack 98 is provided with a similar longitudinally extended slot 98a to receive therein the ends of the carriages 93 and 94, respectively. This construction permits the carriage 93 to extend for a substantial distance into the tube 91 without interfering with movement of rack 100, and similarly the carriage 94 is permitted to extend for a substantial distance into the tube 90 without interfering with movement of the rack 98. It will be obvious that this arrangement provides a much more satisfactory support of the carriages 93 and 94 to guide them in their movement and prevent lateral displacement thereof.

To control movement of the upper and lower carriages 93 and 94, respectively, there is provided a power assembly unit including the gear 102 best shown in Fig. 3 of the drawings and designated by the reference numeral 105. This power assembly unit includes the motor 49 and comprises a frame 106 of U-shaped configuration having the bight portion thereof suitably bolted or otherwise secured as by the fastening means 107 to the horizontal frame members 58 and 59, whereby the bight of the U-shaped frame member 106 clamps the tubular members 90 and 91 in position and tends to firmly support them at the central portion and maintain them in vertical alignment. As indicated, the

gear 102 is mounted on a horizontally disposed shaft 107 journalled in bearing members defined in frame members 109 and 110 suitably welded to the legs and bight respectively of the U-shaped frame member 106. The gear member 102 is keyed to the shaft 107 as indicated at 112 in Fig. 8 of the drawings. The shaft 107 is furthermore provided with one or more flat surfaces at the end 107a thereof to receive a manually actuatable knob 111 whereby the gear 102 may be manually rotated as desired. The motor 40 is also adapted to drive the gear 102 through a suitable reduction gear mechanism comprising a worm gear 113 mounted on the motor shaft which worm gear meshes with a gear 114 rotatable with a horizontally disposed shaft 115 forming part of the power unit 106. Also disposed on the shaft 115 is a small gear 116 drivingly engaged with a large gear 117 disposed on the shaft 107. The arrangement of these gears is such that a substantial speed reduction occurs between the shaft of the motor 40 and the shaft 107.

For the purpose of permitting manual rotation of the gear 102 without interfering with the operation of the motor 40, a suitable friction clutch is provided between the gear 117 and the gear 102. As illustrated, a friction member 118 best shown in Fig. 8 of the drawings is disposed between the adjacent faces of the gears 102 and 117. In addition, a friction plate 119 biases a friction washer 120 against the other face of the gear 117. The friction members 118 and 120 are biased into frictional engagement with the surfaces of the gears 117 and 102 by virtue of a compression spring 121 clearly shown in Fig. 8 of the drawings. Under normal conditions rotation of the gear 117 will cause rotation of the gear 102 by virtue of the friction member 118 interposed therebetween. However, when the shaft 107 is manually rotated, slippage occurs between the gear 117 and the gear 102.

In order to support the lower carbon electrode 28 from the carriage 94, there is provided a suitable casting 125 which is fastened as by fastening means 126 to the carriage 94. This casting includes a carbon clamping portion 127 for clampingly engaging the lower carbon electrode 28 so as to support it in a vertical position for movement along a vertical axis. This clamping portion 127 is electrically insulated by suitable means not shown from the carriage 94 so that conductor 25b may be electrically connected to clamping means 127. The reflector 11 is provided with suitable openings 11b and 11c wherethrough the ends of the carbon electrodes may extend to permit the arc to be drawn within the reflector 11. These openings are preferably large enough so that a portion of the carbon support, such, for example, as carbon clamping means 127, may also be received to permit utilization of the maximum amount of the carbons.

In order to support the upper carbon 27 from the upper carriage 93 there is provided, as best shown in Figs. 3 and 9 of the drawings, a suitable casting 130 which is bolted or otherwise secured to the upper carriage 93. This casting 130 includes an opening 131 defined therein for receiving a hollow insulating bushing 133 preferably formed of lava or other suitable material which is a satisfactory electrical insulator and at the same time is capable of withstanding high temperatures. The upper electrode 27 is adapted to be slidingly disposed within the central opening of the bushing 133.

As was mentioned above, the arc striking solenoid 50 is capable of causing high speed separation of the carbons 27 and 28 in order to draw the arc initially, and to this extent it is desirable for the carbons to contact each other when no current flows therethrough. It is for this reason that the upper carbon 27 is reciprocally movable in the lava bushing 133. To insure straight line motion of the carbon 27 during the movement produced by the solenoid 50, there is provided a straight line motion mechanism comprising a carbon lift plunger 134 reciprocally movable in a suitable recess defined in the casting 130 which recess has its longitudinal axis parallel with the axis of the carbon electrode 27. This lift plunger 134 is connected by a link 135 having a forked end 135a for engaging a head 136 suitably clamped as by clamping means 137 to the upper carbon 27. The link 135 is insulated from the carbon lift plunger 134 by means of suitable mica washers disposed above and below the link 135 where it is fastened to the plunger 134 and an insulating bushing surrounding the portion of the plunger 134 which preferably passes through a suitable opening in the link 135. The lift plunger 134 is provided with a head 140 which is bifurcated to receive therein a link 141 pivotally connected thereto by pin 142. This link in turn is pivotally connected to one end of a lever 146 which lever is pivotally connected as indicated at 147 to the casting 130. The other end of the lever 146 is connected by a short link 150 with the armature 51 of the solenoid 50. Energization of the solenoid 50 will cause the armature 51 to move downwardly as viewed in Fig. 3 of the drawings and hence will cause relative separation between the carbons 27 and 28. When the solenoid 50 is deenergized, as indicated in Fig. 3, then the upper carbon 27 is moved downwardly so as physically to engage the lower carbon 28. As soon as current flows through the carbon electrodes 27 and 28, the solenoid 50 is energized to cause separation of the electrodes 27 and 28 with the consequent production of an arc therebetween. The lower carbon 28 is so disposed that the arc is drawn at the center of the reflector 11. In order to aid gravity in causing the electrodes 27 and 28 to move to the position shown in Fig. 3 when the solenoid 50 is deenergized, a suitable compression spring 151 is provided which tends to bias the armature 51 into the position indicated in Figs. 3 and 4 of the drawings. It will be understood that the armature 51 must also be supported from the carriage 93 and preferably the same bolts or fastening means for holding the casting 130 to the carriage 93 also hold the solenoid 50 in position with respect to this carriage.

For the purpose of electrically connecting the upper electrode 27 with the power source, there is provided an insulated lead 152 which is connected to the member 136 and to a terminal 153 suitably insulated as by means of an insulator 154 from the lever 146 at the pivot point 147. Power is supplied to this terminal which is relatively stationary in the manner shown in Fig. 2 of the drawings through the conductor 25a which is included in the cable 25.

Supported from the lower end of the frame 54 is a carbon drip pan 157 for receiving any arc particles produced when arc current flows between the electrodes 27 and 28. Preferably a suitable Allen wrench 160 is supported from a chain or other flexible member attached to the frame 54 which wrench is employed to control

the clamping motion for the upper and lower carbon holders 127 and 137 when it is necessary to change the carbons.

In view of the detailed description included above, the operation of the present invention will readily be understood by those skilled in the art. The reflector 11 is initially adjusted at the proper vertical height and at the proper angle, both horizontal and vertical, through suitable manipulation of the manually adjustable levers 65 and 78. It is assumed that the electrodes 27 and 28 are normally in the position indicated in Fig. 3 of the drawings. Upon closing the switch 29, the volt meter 40 indicates the voltage of the source 28 and the tap changing switches 33 and 34 are adjusted for the proper range of voltage to assure a uniform arc temperature and consequently uniform illumination under all conditions. Upon closing of the switch 29 with the carbon electrodes 27 and 28 in the position indicated in Fig. 3, current will flow through the conductors 25a and 25b and consequently through the carbon electrodes 27 and 28. This current will also flow through the serially arranged windings 31' and 32' of the relays 31 and 32, respectively. The latter will close its contacts 32a to energize the arc striking solenoid 50 which will separate the electrodes 27 and 28 to draw an arc therebetween, by moving the upper carbon 27 upwardly to the limit of movement of the solenoid 50. This solenoid will remain energized as long as current flows through these carbon electrodes 27 and 28. The sensitive current relay 31 will very accurately maintain at a constant value the current flowing through the arc through operation of the motor 40 in a forward or reverse direction as the case may be. This current will remain constant regardless of voltage changes of the power source 28, and regardless of the impurities bound to be included in the carbon electrodes 27 and 28 which cause these carbons to have hard spots or soft spots as the case may be. Since the initial arc current is accurately controlled with respect to the initial voltage conditions of the system and actually standardized by means of the tap changing switches 33 and 34 the same Kelvin temperature of the arc can be obtained for all conditions, and hence a constant source of illumination, which will greatly improve conditions in the graphic arts industry, is provided.

The arrangement for supporting the upper electrode 27 described thus far limits the amount of the electrode which can be consumed, and in Figs. 10 and 11 of the drawings there is illustrated a modification of the supporting means for the carbon electrodes whereby a substantially greater use of the carbons is possible. As illustrated in Fig. 10, there is provided an upper casting 160 which corresponds to the casting 130 of Fig. 3 of the drawings. One end of this casting is suitably secured to the upper movable carriage 93. The end of this casting not fastened to the movable carriage 93 is provided with a rectangular opening 161 arranged in a vertical position to receive therein for sliding reciprocating movement with respect thereto a carbon guide plunger 163 of rectangular cross section. The opening 161 is of sufficient length and by virtue of its rectangular cross section will limit movement of the lift member 163 to movement only in the direction of its longitudinal axis. The upper end of the lift rod 163 is connected by a suitable link 164 with one end of a lever 165 pivotally mounted as indicated at 166 to the casting 160. The other end of the lever 165 is pivotally connected by means of the

link 150 to the solenoid armature 51. It will be apparent that energization of the solenoid 50 will cause vertical movement of the lift rod 163.

The lower end of the lift rod 163 disposed beneath the opening 161 in the casting 160 is fastened by suitable stud bolts 168 or the like, to a carbon clamp member 170, which is provided with a V-shaped notch 170a for receiving therein the upper carbon electrode 27. A suitable 10 clamping plate 171, maintained in clamping position by the clamping screw 172, holds the electrode 27 in the notch 170a. The clamping screw 172 is illustrated as having an enlarged head 172a with suitable openings 172b therein for manipulation by a clamp wrench, not shown. The carbon clamp 170 is insulated from the lift rod 163 by mica insulating plates 175 and 176 and mica sleeves 177. As is best shown in Fig. 11 of the drawings, the conductor 25a may then be connected to the carbon clamp 170 by a suitable terminal screw 179.

As illustrated in Fig. 10, the lower carbon 28 is supported by a lower carbon clamp 170 identical in every respect with the upper carbon clamp just described, thus making for ready interchangeability of parts. This lower carbon clamp 170 is supported from a lower casting 180 which in turn is supported from the lower carbon carriage 94. The lower carbon clamp 170 is similarly insulated 30 from the casting 180 by the mica insulators 175 and 176 and the sleeve insulators 177 so that electrical connection with the conductor 25b through a terminal connection 179 may readily be made.

From the above description it will be apparent that the upper and lower carbons 27 and 28 may be utilized to substantially their entire extent with only the small portions retained within the clamps 170 not being useable. In addition, the 40 arrangement permits of electrical connections being made directly to the clamps 170.

While there have been illustrated and described several embodiments of the present invention, it is not desired that the invention be limited to the constructions shown and described, 45 for it will, of course, be obvious to those skilled in the art that changes and modifications may be made without departing from the invention in its broader aspects, and it is, therefore, aimed in the appended claims to cover all such changes and modifications as fall within the true spirit and scope of this invention.

What is claimed as new and desired to be secured by Letters Patent of the United States is:

55 1. In an arc lamp comprising a pair of electrodes between which an arc is adapted to be drawn, the combination of a pair of electrode carriages each capable of supporting one of said electrodes, an electric motor for moving said carriages simultaneously in opposite directions to control the arc space between said electrodes, a power circuit connected to said electrodes, an electromagnet for moving one of said electrodes relative to the other, a relay including a winding 60 connected in series with said power circuit, means responsive to operation of said relay for energizing said electromagnet to move said one electrode, and arc current responsive means for controlling the energization of said electric motor to cause simultaneous movement of said electrodes in a manner to tend to maintain constant the arc current flowing between said electrodes.

65 2. In an arc lamp comprising a pair of electrodes between which an arc is adapted to be drawn, the combination of a pair of electrode

carriages each capable of supporting one of said electrodes, a first motive means for moving said carriages simultaneously in opposite directions to maintain a predetermined arc space between said electrodes, a power circuit connected to said electrodes, second motive means comprising an electromagnet for moving one of said electrodes relative to the other, a relay including a winding connected in series with said power circuit, means responsive to operation of said relay for actuating said second motive means to move said one electrode, and arc current responsive means for controlling said first motive means to cause simultaneous movement of said electrodes in a manner to tend to maintain constant the arc current flowing between said electrodes.

3. In an arc lamp comprising a pair of electrodes between which an arc is adapted to be drawn, the combination of a pair of electrode carriages each capable of supporting one of said electrodes, a first motive means for moving said carriages simultaneously in opposite directions to maintain a predetermined arc space between said electrodes, a power circuit connected to said electrodes, second motive means for moving one of said electrodes relative to the other, a first relay and a second relay each including a winding connected in series with said power circuit, means responsive to operation of said first relay for actuating said second motive means to move said one electrode, and means responsive to operation of said second relay for controlling said first motive means to cause simultaneous movement of said electrodes in a manner to maintain constant the arc current flowing between said electrodes.

4. In an arc lamp, the combination of a frame, upper and lower carbon carriages mounted for relative movement on said frame, means for supporting a carbon from each of said carriages in colinear relationship, a first rack connected to said upper carbon carriage, a second rack connected to said lower carbon carriage, the longitudinal axes of said racks being disposed in spaced parallel relationship, a gear for engaging both of said racks to cause simultaneous movement of said racks in opposite directions, motive means connected to said gear, and means responsive solely to current flowing through said carbons for controlling said motive means to maintain a predetermined arc space between said carbons.

5. In an arc lamp, the combination of a pivotally supported frame, upper and lower carbon carriages mounted for relative movement on said frame, means for supporting a carbon from each of said carriages in colinear relationship, a first rack connected to said upper carbon carriage, a second rack connected to said lower carbon carriage, the longitudinal axes of said racks being disposed in spaced parallel relationship, a gear for engaging both of said racks to cause simultaneous movement of said racks in opposite directions, electric motor means drivingly connected to said gear, means for controlling said electric motor to maintain a predetermined space between said carbons, an electromagnet connected to move only one of said carbon carriages relative to the other, and arc current responsive means responsive to current flowing in the arc drawn between said carbons for controlling the energization of said electromagnet.

6. In an arc lamp comprising a pair of electrodes between which an arc is adapted to be drawn, the combination of a pair of electrode

carriages each capable of supporting one of said electrodes, a first motive means for moving said carriages simultaneously in opposite directions to maintain a predetermined arc space between said electrodes, a power circuit connected to said electrodes, second motive means comprising an electromagnet for moving one of said electrodes relative to the other, a first relay and a second relay each including a winding connected in series with each other and in series with said power circuit, means responsive to operation of said first relay for actuating said second motive means to move said one electrode, and means responsive to operation of said second relay for controlling said first motive means to cause simultaneous movement of said electrodes in a manner to maintain constant the arc current flowing between said electrodes.

7. In an arc lamp comprising a pair of electrodes between which an arc is adapted to be drawn, the combination of a pair of electrode carriages each capable of supporting one of said electrodes, an electric motor for moving said carriages simultaneously in opposite directions to maintain a predetermined arc space between said electrodes, a power circuit connected to said electrodes, an electromagnet for moving one of said electrodes relative to the other, a first relay and a second relay each including a winding connected in series with each other and in series with said power circuit, means responsive to operation of said first relay for energizing said electromagnet to move said one electrode, and means responsive to operation of said second relay for controlling the energization of said electric motor to cause simultaneous movement of said electrodes in a manner to maintain constant the arc current flowing between said electrodes.

8. In an arc lamp, the combination of a supporting frame, a pair of tubular members mounted on said frame with their longitudinal axes disposed in spaced parallel relationship, a pair of racks one disposed within each of said tubular members and each movable along one of said axes, a gear disposed between said tubular members at an intermediate position with respect thereto and drivingly engaged with each of said racks whereby rotation of said gear causes simultaneous movement of said racks in opposite directions, means defining a longitudinally extending groove in adjacent faces of each of said members at both ends thereof, a first movable carriage extending into the grooves at one end of each of said members, means for fastening said first carriage to one end of one of said racks within the corresponding one of said members, a second movable carriage extending into the grooves at the other end of each of said members, means for fastening said second carriage to the other end of the other of said racks disposed within the other of said members, and longitudinally extending grooves defined in the ends of said racks to which no carriage is attached for receiving therein a portion of the carriage adjacent that end of the rack when said carriages are moved a predetermined distance towards each other.

9. In an arc lamp, the combination of a supporting frame, a pair of tubular members of rectangular cross section mounted on said frame with their longitudinal axes disposed in spaced parallel relationship, a pair of racks one disposed within each of said tubular members and each movable along one of said axes, a gear dis-

posed between said tubular members at an intermediate position with respect thereto and drivingly engaged with each of said racks whereby rotation of said gear causes simultaneous movement of said racks in opposite directions, means defining a longitudinally extending groove in adjacent faces of each of said members at both ends thereof, a first movable carriage extending into the grooves at one end of each of said members, means for fastening said first carriage to one end of one of said racks within the corresponding one of said members, a second movable carriage extending into the grooves at the other end of each of said members, means for fastening said second carriage to the other end of the other of said racks disposed within the other of said members, and longitudinally extending grooves defined in each of the ends of said racks to which no carriage is attached for receiving therein a portion of the carriage attached to the corresponding end of the other of said racks when said carriages are moved a predetermined distance towards each other.

10. In an arc lamp, the combination of a supporting frame comprising a pair of angle members and cross members united to form a ladder like frame, a pair of tubular members mounted on said frame with their longitudinal axes disposed in spaced parallel relationship, a pair of racks one disposed within each of said tubular members and each movable along one of said axes, a gear disposed between said tubular members at an intermediate position with respect thereto and drivingly engaged with each of said racks whereby rotation of said gear causes simultaneous movement of said racks in opposite directions, means defining a longitudinally extending groove in adjacent faces of each of said members at both ends thereof, a first movable carriage extending into the grooves at one end of each of said members, means for fastening said first carriage to one end of one of said racks within the corresponding one of said members, a second movable carriage extending into the grooves at the other end of each of said members, means for fastening said second carriage to the other end of the other of said racks disposed within the other of said members, means for supporting in coaxial relationship a pair of carbon electrodes one mounted on each of said carriages, and means for automatically rotating said gear in a manner to produce constant illumination of an arc drawn between said carbon electrodes.

11. In an arc lamp, the combination of a supporting frame, a pair of tubular members mounted on said frame with their longitudinal axes disposed in spaced parallel relationship, a pair of racks one disposed within each of said tubular members and each movable along one of said axes, a gear disposed between said tubular members at an intermediate position with respect thereto and drivingly engaged with each of said racks whereby rotation of said gear causes simultaneous movement of said racks in opposite directions, means defining a longitudinally extending groove in adjacent faces of each of said members at both ends thereof, a first movable carriage extending into the grooves at one end of each of said members, means for fastening said first carriage to one end of one of said racks within the corresponding one of said members, a second movable carriage extending into the grooves at the other end of each of said members, means for fastening said second carriage to

the other end of the other of said racks disposed within the other of said members, a reversible electric motor drivingly connected to said gear, manual means also connected to said gear, and a friction clutch for permitting actuation of said manual means without interference from said electric motor.

12. In an arc lamp, the combination of a pair of movable electrode carriages for supporting a pair of electrodes movable towards and away from each other along a line comprising the longitudinal axes of said electrodes, means for supporting said carriages for simultaneous movement in opposite directions, a source of potential which may vary in voltage within predetermined limits, an electric circuit connecting said source with said electrodes including a transformer, means for adjusting the potential output of said transformer to a predetermined value regardless of the potential of said source, motive means for moving said electrodes, and control means responsive solely to the current flow through said electrodes for controlling said motive means for maintaining constant the current flow through said electrodes.

13. In an arc lamp, the combination of a pair of movable electrode carriages for supporting a pair of electrodes movable towards and away from each other along a line comprising the longitudinal axes of said electrodes, means for supporting said carriages for simultaneous movement in opposite directions, a source of potential which may vary in voltage within predetermined limits, an electric circuit connecting said source with said electrodes including a transformer having primary and secondary windings, a plurality of taps on said primary winding for adjusting the voltage across said secondary winding to a predetermined value regardless of the potential of said source, motive means for moving said electrodes, and control means responsive solely to the current flow through said electrodes for controlling said motive means for maintaining constant the current flow through said electrodes.

14. In an arc lamp, the combination of a frame, upper and lower carbon carriages mounted for relative movement on said frame, means for fixedly supporting a lower carbon electrode from said lower carriage, a lever pivotally supported from said upper carriage, means for supporting an upper carbon electrode from said upper carriage to permit limited relative movement with respect to said carriage, the longitudinal axes of said electrodes being colinear and movement of said electrodes being limited solely to movement along said colinear axes, means for connecting one end of said lever to said last mentioned means, and motive means connected to the other end of said lever.

15. In an arc lamp, the combination of a frame, upper and lower carbon carriages mounted for relative movement on said frame, means for fixedly supporting a lower carbon electrode from said lower carriage, a lever pivotally supported from said upper carriage, means for supporting an upper carbon electrode from said upper carriage to permit limited relative movement with respect to said carriage, the longitudinal axes of said electrodes being colinear and movement of said electrodes being limited solely to movement along said colinear axes, means for connecting one end of said lever to said last mentioned means, and an electromagnet having its armature connected to the other end of said lever to

cause movement of said upper electrode in a direction away from said lower electrode.

16. In an arc lamp, the combination of a frame, upper and lower carbon carriages mounted for relative movement on said frame, means for fixedly supporting a lower carbon electrode from said lower carriage comprising a lower carbon clamp, a lever pivotally supported from said upper carriage, means for supporting an upper carbon electrode from said upper carriage to permit limited relative movement with respect to said carriage including an upper carbon clamp identical with said lower carbon clamp, the longitudinal axes of said electrodes being colinear and movement of said electrodes being limited solely to movement along said colinear axes, means for connecting one end of said lever to said last mentioned means, an electromagnet having its armature connected to said lever to move said upper carbon away from said lower carbon to draw an arc therebetween, and means responsive to the current flow through said electrodes for energizing said electromagnet.

17. In an arc lamp, the combination of a frame, upper and lower carbon carriages mounted for relative movement on said frame, means for supporting a carbon from each of said carriages in colinear relationship, a first rack connected to said upper carbon carriage, a second rack connected to said lower carbon carriage, the longitudinal axes of said racks being disposed in spaced
